UNITED STATES PATENT OFFICE.

JAMES P. DOVEL, OF BIRMINGHAM, ALABAMA.

PORTABLE WASHING PLANT.

1,309,754.

Specification of Letters Patent. Patented July 15, 1919.

Application filed September 21, 1915. Serial No. 51,881.

To all whom it may concern:

Be it known that I, JAMES P. DOVEL, a citizen of the United States of America, residing at Birmingham, in the county of Jefferson and State of Alabama, have invented 5 certain new and useful Improvements in Portable Washing Plants, of which the following is a specification.

My invention relates to a portable washing apparatus which is capable of being transported to the point where the material to be treated is excavated and to there effect a substantial washing of the material so that it is necessary only to transport the 15 desired portion of the material to the point of further treatment.

My invention was conceived as a means for improving the present methods of mining, separating and washing brown ore, but 20 it is obviously capable of adaptation to other analogous uses.

According to the present practice the brown ore, together with a large proportion of clay, gravel and other foreign matter, is 25 excavated and transported from the various mines to a stationary washing plant where the ore is washed, picked and delivered to railway cars or lorries for transportation to the furnace. Inasmuch as the 30 ore constitutes generally about one-fifth of the material excavated and transported to the washer, it will be evident that a considerable expense is unnecessarily incurred in transporting the raw material to the 35 washer and I have conceived that if a portable washer is designed so that it will treat the excavated material at the mine so as to effectually separate the ore therefrom, marked economy in operation will be obtained as then it will be necessary only to 40 transport the washed ore either directly to the furnace, or, if desired, to a further washing plant for final treatment.

With these objects in view I have designed 45 a portable carriage upon which is mounted a plurality of rotating screens, one having a plurality of holes and the other small large diameter holes and the other small diameter holes, and these are driven by a small power plant on the carriage which 50 is also adapted to drive an elevator by means of which the washed material can be delivered to cars or lorries.

One feature of my invention which is of 55 particular importance in a portable washing plant is the concentric arrangement of the two perforated screening cylinders one

within the other and providing means to deliver clay and smaller lumps of ore after a preliminary screening into the inner rotating screen which has the larger diameter of 60 openings.

A further feature of my invention relates to the provision of a forced feed means for the material both inside and outside of the two screening cylinders, the advantage of 65 this arrangement being that the washer can operate at nearly any inclination which the nature of the work offers and it is not necessary to provide a level foundation. Moreover by avoiding the gravity feed the screens 70 can be disposed horizontally and thus bring their feed hopper low enough to conveniently receive the material from the steam shovels.

A further feature of my invention relates 75 to the arrangement of the sludge tank which opens in its upper portion into the boot of the elevator, the latter receiving the screened material from the two rotating screens, which material the elevator discharges into 80 cars, when the apparatus is worked to recover the lump material or the elevator discharges the lumps to the waste when the apparatus is worked to recover the fines or sludge. In this connection the power plant 85 is adapted to operate a centrifugal pump to lift and discharge the sludge at any desired point.

My invention further comprises the novel means of applying water so that it will 90 most effectively wash the material being treated by the screens.

My invention further comprises other novel details of construction and arrangements of parts which in their preferred embodiments only are hereinafter disclosed and are illustrated in the accompanying drawings forming a part of this specification, and in which:

Figure 1 is a top plan view of the apparatus with the cab cover removed.

Fig. 2 is a longitudinal vertical sectional view taken on the line $x-x$ of Fig. 1 with the cab partly broken away.

Figs. 3 and 4 are cross sectional views of 105 Fig. 1 (the latter being enlarged), taken on the lines 3-3 and 4-4, respectively.

Similar reference numerals refer to similar parts throughout the drawings.

My apparatus is mounted upon an angle 110 iron bed frame 1 having forward steering wheels 2 and rear driving wheels 3, the lat-

ter being adapted to be driven by gears 4 through suitable transmission from a motor 5 that may be of any suitable type, but is preferably an electric motor where current 5 is obtainable. A second motor 6 is provided and adapted, through a suitable gearing, to drive a shaft 7 which extends substantially from end to end of the frame and is mounted to rotate in end bearings 10. At the forward end of the apparatus I provide a hopper 9 having one side cut away to provide for an overhanging chute 10 preferably disposed level with the flat bottom of the hopper in which is provided 15 a screen grating 11 formed of parallel bars spaced sufficiently to pass all but the larger lumps of ore and rock deposited in the hopper. Below the hopper is a sloping bottom 12 which terminates in a lateral annular dis- 20 charge chute 13 which delivers the preliminary screened material into the forward end of the inner rotatable screen 14 formed by a perforated cylindrical metal drum mounted by the spiders 15 on the shaft 7. Within 25 the screen 14 I mount a series of spaced angle bars 16 forming internal ribs which extend lengthwise thereof and have a slight spiral arrangement to prevent the accumula- 30 tion of material at the inner end of this screen, and force it to move lengthwise through the screen. The perforations in the screen 14 are of substantial diameter, being 35 preferably large enough to freely pass half inch material. The outer screen 17, formed by a perforated cylindrical metal drum, is mounted concentrically about the screen 14, having the same length and being connected in spaced relationship to the screen 14 by 40 means of a spirally disposed rib 18 which extends from end to end of the screens and is designed to serve as a feed screw for the material between the screens. The perforations in the outer screen 17 are of very small diameter, such, for instance, as an eighth 45 of an inch, so that only the fines or the sludge will pass therethrough. The screen 17 works in a semi-circular trough 19 which is struck on a curve from the center of the shaft 7 and is suitably mounted on the frame 50 so as to be sufficiently spaced from the outer periphery of the screen 17 to receive a spiral screw feed rib 20 disposed about the outer periphery of the screen 17, and adapted to discharge the sludge from the trough. 55 The forward end wall 21 of the trough is cut away to receive and support the chute 13 and to close the forward ends of the screens. At its rear end the trough discharges in a sludge tank 22 having at its 60 bottom on one side an outlet pipe 23. The two rotary screens 14 and 17 project through the side wall 24 and discharge in an elevator boot which is preferably formed in and communicates with the upper portion 65 of the sludge tank 22 and has its bottom

wall 26 sloping downwardly and joining the outlet side wall of the tank immediately above pipe 23. An endless bucket elevator 27, supported by suitable frame work 28, works in the elevator boot and serves to lift 70 the screened ore or material that is discharged into the boot from the inside of the two screens and deliver it to a chute 29 at an elevation sufficient to fall into a railroad car or lorry. A water outlet pipe 75 30 leads from the elevator boot and connects with the pipe 23, and I provide a valve 31 in the pipe 23 between the tank 22 and pipe 30 and I adjust this valve to back up the water in tank 22 until it overflows into the 80 elevator boot and maintains the desired quantity of water therein. The water has a free outlet from the boot through pipe 30, so the apparatus will not flood.

Water from any suitable source of supply 85 is passed through a hose 32 to a spray pipe 33 which extends lengthwise over the top of the screen 17 and connects with a spray pipe 34 which passes around the hopper 9 immediately below the screen bars 11 there- 90 in. The sludge tank is preferably under- hung from the frame.

The power plant for the apparatus is pro- 95 tected by a cab 35 at the rear end of the frame and I provide at one side of the cab 35 a platform 36 upon which the operator stands and guides the carriage by means of a steering wheel 37, the shaft 38 of which passes above the near driving wheel 3 and operates a steering gear 39 which is connected by chains 40 to the forward steer- 100 ing wheels 2.

In operation, the apparatus, having been driven under its own power to the point where the ore or other material to be treat- 105 ed is being excavated, the material as excavated by steam shovels is dumped into the hopper 9 where it is worked over the screen bars 11, the large lumps being thrown off the chute 10 and the smaller lumps, dirt and 110 gravel passing through the chute 13 and into the inner screen 14. As the screens rotate the ribs 16 feed the largest lumps longitudinally through the screen 14 until they finally fall into the elevator boot. The gravel, 115 small lumps and sludge pass through the screen 14 and fall upon the screen 17 where they are acted upon by the spiral rib 18 and fed lengthwise along the screen 17, the sludge working through the small apertures 120 in the screen 17 and the small lumps and pieces of ore larger than one-eighth inch, which cannot pass through this screen 17, are finally discharged also into the boot of the elevator. The sludge is fed lengthwise 125 of the trough 19 by the external spiral rib 20 about the screen 17 and discharged into the sludge tank. The sludge tends to settle in the bottom of the sludge tank from which it is gradually withdrawn through the out- 130

let pipe 23 at such a rate that the water level in the tank will be maintained above the top of the elevator boot so as to maintain the latter full of water so that the elevator buckets dip therein and work under water in picking up the ore, the excess water, as the buckets rise, draining back into the tank. The water sprays from the pipe 33 and serves to keep the screen 17 clean and to further wash the large and small lumps inside the two screens. By having a forced feed for the material the carriage can operate on an incline with its forward end well below its rear end and by avoiding inclining the screens and having the underhung sludge tank, the hopper 9 is brought to a convenient level for receiving the material from the steam shovel.

In the event the apparatus is working down a slope it may be necessary to pump away the sludge and for this purpose a main power shaft 41, which is driven by the motor 5, is provided with a clutch 42 by means of which the motor can be disconnected from the driving gearing and adapted to drive a shaft 43 carrying a pulley 44. A small centrifugal pump 45 (see Fig. 3) may be connected to the pipe 23 and driven by a belt (not shown) from the pulley 44.

It will be obvious that when the object of the operation is to recover and treat the fines or sludge, the material dumped from the elevator and from chute 10 will go to the waste and all of the sludge can be pumped from the pipe 23 to the point of treatment. My apparatus may be thus adapted to a variety of mining purposes for which a portable washing plant would prove valuable.

Having thus described my invention, what I claim as new and desire to secure by Letters Patent, is:—

1. In a portable ore washer, a wheeled

frame, a hopper set low on said frame and adapted to receive material from a steam shovel, a stationary screen in the hopper, a feed chute under said screen, a double rotating screen horizontally disposed under said chute arranged to discharge into one end, positive helical feed means to advance the material lengthwise in the screen, a sludge trough mounted closely under the screen, a helical feed screw carried by the screen and adapted to force the feed of sludge lengthwise of said trough, an underhung sludge tank into which said trough discharges, and an elevator boot mounted in said tank below the normal water level therein and disposed beneath the discharge ends of said screen.

2. In a portable ore washer, rotatable screening means and a sludge trough mounted thereunder, a sludge tank into which said sludge trough discharges, an elevator boot mounted in the sludge tank with its open top below the normal water level therein and under the discharge end of said screening means, and a valve controlled sludge outlet for said sludge tank.

3. In a portable ore washer, rotatable screening means and a sludge trough mounted thereunder, a sludge tank into which said sludge trough discharges, an elevator boot mounted in the sludge tank with its open top below the normal water level therein and under the discharge end of said screening means, a valve controlled sludge outlet for said sludge tank, and an overflow outlet for the tank and boot leading from the latter, substantially as described.

In testimony whereof I affix my signature. 80

JAMES P. DOVEL.
